UNITED STATES PATENT OFFICE.

ARTHUR WILLIAM SCLATER, OF WESTMINSTER, LONDON, ENGLAND.

FITTING FOR CONDUITS FOR ELECTRICAL CONDUCTORS.

1,246,333.

Specification of Letters Patent.

Patented Nov. 13, 1917.

Application filed December 17, 1915. Serial No. 67,406.

To all whom it may concern:

Be it known that I, ARTHUR WILLIAM SCLATER, a subject of the King of England, residing at 14 Sackville street, Piccadilly, 5 in the city of Westminster, London, England, have invented certain new and useful Improvements in Fittings for Conduits for Electrical Conductors, of which the following is a specification.

10 This invention relates to fittings for conduits for electrical conductors and refers to an improved construction of such devices, by the use of which the conduits can be easily fixed in position, more cheaply and expeditiously than is the case with the fittings at present in use.

Metal conduits for electrical conductors, when erected, should be electrically and mechanically continuous throughout.

20 The conduit generally employed consists of lengths of metallic tubing, with screwed ends, which engage with internally screwed connectors, sockets, boxes or other fittings, thus forming a continuous electrical and mechanical system.

According to my invention I do away with all screwed tubes, screwed sockets and other screwed fittings and pinching screws, and also with all eccentric boring of sockets, 30 projections, segmental cam surfaces and other intricate contours, and I connect the tube forming the conduit to the outlet of the box socket or other fitting of metal herein-after called the outlet, in the following manner:—

The interior of the outlet is slightly elliptical in form and into this outlet I place a hollow metal connecting piece, the outer surface of which is also slightly elliptical in 40 form, which connecting piece slides easily into the outlet, the major axes of the two ellipses coinciding.

The inner surface of the connecting piece is circular in form and is of such size as to 45 fit tightly the outside of the tube forming the conduit, which is pushed into it, the tube, the connecting piece and the outlet being all concentric.

The connecting piece is provided with an 50 enlarged end, of hexagonal or other shape with which a wrench or spanner can engage. The socket box or other fitting is held firmly, and the connecting piece is turned as far as possible in either direction.

55 The effect of turning the connecting piece is that the major axis of such piece is forced

as far as it will go toward the minor axis of the outlet, and in being so forced the interior of the connecting piece is distorted with the result that the tube forming the 60 conduit inside it, is gripped very tightly and at the same time the exterior surface of the connecting piece is tightly wedged against the interior surface of the outlet.

In some cases it is advisable to form a 65 longitudinal saw cut or slit in the connecting piece so as to permit the interior bore of such piece being reduced in size so as to grip the tube forming the conduit.

In order that my invention may be clearly 70 understood, I will now proceed to describe the same with reference to the accompanying drawings in which:—

Figure 1 represents a side elevation of a 75 socket and two connecting pieces, forming a coupling by means of which two tubes are connected.

Fig. 2 represents an end elevation of the same coupling.

Fig. 3 represents the same coupling in longitudinal section.

Fig. 4 represents the same coupling in cross section.

Fig. 5 shows a circular box, partly in section provided with two outlets formed in accordance with my invention.

Fig. 6 shows a cross section of the outlet of the same box, when the connecting piece is just slipped in and with a conduit tube in position.

Fig. 7 shows a cross section of the same outlet with the connecting piece forced around to its gripping position.

Fig. 8 is a longitudinal section illustrating a modified form of connecting piece 95 hereinafter more fully described.

The same letters of reference are employed to denote the same parts in all the views:—

a is the socket, by means of which the tubes *b b* forming the conduit are coupled together—see Figs. 1 to 4. The interior of the socket outlets is slightly elliptical in form, the major axis on *c d* being greater than the minor axis on *e f*.

100 Into each outlet *a* of the socket is slipped a connecting piece *g*, the exterior surface of which is slightly elliptical, the major axis on *c d* being greater than the minor axis on *e f* the connecting piece *g* may have a longitudinal slit or saw cut *h*, and the interior 105 surface of the connecting piece *g* fits the outer surface of the tube *b* forming the con-

duit; the tube, the connecting piece and the outlet being concentric.

The end of the connecting piece outside the socket, is formed with a hexagonal head *j* 5 by means of which the said connecting piece *g* may be turned inside the socket *a*, so that the major axis of the connecting piece is forced toward the minor axis of the socket. As a result the inner surface of the connecting piece *g* is distorted or reduced, the longitudinal slit or saw cut *h*, where such is provided closing up and the tube being tightly gripped by the inside of the connecting piece *g*, while at the same time the outer 15 surface of the connecting piece is tightly wedged against the inner surface of the socket. Thus in addition to a strong mechanical joint, good electrical continuity is made between the tubes *b* forming the 20 conduit.

It will be readily understood that half of a socket such as *a* can form the outlet of a box or other fitting to which a conduit *b* has to be connected.

25 An arrangement of this description is shown at Figs. 5 to 7.

In these figures *a a* are the outlets of the box which outlets are formed in the same manner as the socket in Figs. 1 to 4. *b b* are 30 the tubes forming the conduit. The inner surface of the outlets *a a* is slightly elliptical in form, the major axis on *c d* being greater than the minor axis on *e f*, *g* is a connecting piece, the outer surface of which 35 is slightly elliptical the major axis *c d* being greater than the minor axis *e f*. The connecting piece *g* is formed with a hexagonal head *j*, and the longitudinal saw cut or slit *h* is also preferably provided therein.

40 In fitting the parts in position the tube forming the conduit *h* is inserted into the connecting piece *g* which, in turn is inserted into the outlet *a*. On turning the connecting piece *g* by means of the hexagonal head 45 *j*, the major axis on *c d* is moved toward the position *c¹ d¹*, the connecting piece *g* being thereby compressed on the line *c¹ d¹* and the interior bore being reduced, the tube is tightly gripped and at the same time the 50 outer surface of the connecting piece *g* is wedged against the interior of the surface of the outlet *a*, thus forming a strong mechanical, as well as a good electrical joint.

In practice it is desirable to eliminate all 55 sharp ledges or projections in the conduit and in order to effect this it is advisable to form the outlet with a step or shoulder *k* as shown in Fig. 5 against which the tube forming the conduit *b* and the connecting 60 piece *g*, butt, the inner surface of the tube coming flush with the inner edge of the shoulder *k* or, as an alternative the connection illustrated at Fig. 8 may be adopted. In this case the connecting piece *g* is provided 65 at the inner end with an inwardly

projecting step or flange *m* against which the inner end of the tube *b* butts, the inner edge of the said flange or step being flush with the interior of the tube *b*. The other side of the flange or step *m* is rounded or 70 beveled off so that no sharp projection is present.

The particular details of the fitting may be varied within the scope of the appended claims. 75

What I claim and desire to secure by Letters Patent of the United States of America is:-

1. A connecting fitting for conduits for 80 electrical conductors, comprising in combination an outlet formed with an elliptical interior, a connecting piece having a corresponding but slightly smaller elliptical exterior adapted to fit into the elliptical interior of the outlet, such connecting piece 85 having a circular interior, adapted to fit closely the outside of the conduit tube to be connected the elliptical interior of the outlet, the elliptical exterior of the connecting piece and the circular interior of the said 90 connecting piece all having a common center and means for enabling the connecting piece to be rotated about its axis for the purposes set forth.

2. A connecting fitting for conduits for 95 electrical conductors comprising in combination an outlet formed with an elliptical interior, a connecting piece having a corresponding but slightly smaller elliptical exterior adapted to fit into the elliptical interior of the outlet, such connecting piece 100 being provided with a longitudinal slit and having a circular interior, adapted to fit closely the outside of the conduit tube to be connected the elliptical interior of the outlet, the elliptical exterior of the connecting piece and the circular interior of the said 105 connecting piece all having a common center and means for enabling the connecting piece to be rotated about its axis for the 110 purposes set forth.

3. A connecting fitting for conduits for 115 electrical conductors, comprising in combination an outlet formed with an elliptical interior, a connecting piece having a corresponding but slightly smaller elliptical exterior adapted to fit into the elliptical interior of the outlet, such connecting piece being provided with a longitudinal slit and 120 having a circular interior adapted to fit closely the outside of the conduit tube to be connected the elliptical interior of the outlet, the elliptical exterior of the connecting piece and the circular interior of the said connecting piece all having a common center, and means associated with the said connecting piece for enabling such piece to be 125 rotated about its axis for the purposes set forth.

4. A connecting fitting for conduits for 130

electrical conductors comprising in combination, an outlet formed with an elliptical interior, a connecting piece having a corresponding but slightly smaller elliptical exterior adapted to fit into the elliptical interior of the outlet, such connecting piece being provided with a longitudinal slit and having a circular interior adapted to fit closely the outside of the conduit tube to be connected, an inwardly projecting flange at the inner end of such connecting piece, such flange forming a step against which the inner end of the conduit is adapted to butt having its inner edge flush with the interior of the conduit when the latter is in position and being rounded off on the other side, the elliptical interior of the outlet, the elliptical exterior of the connecting piece and the circular interior of the said connecting piece all having a common center, and 20 means at the end of the said connecting piece for enabling such piece to be rotated about its axis all substantially as and for the purposes described.

10 In testimony whereof I affix my signature 25
in presence of two witnesses.
